Application October 3, 1930. Serial No. 486,162

4 Claims. (Cl. 250—17)

Our invention relates to radio transmitter devices, and particularly to means incorporated therein for stabilizing the transmission frequency.

5 An object of our invention is to provide means in a radio transmitter system for maintaining the power dissipation in the vacuum tube constant over both the marking and spacing periods, in order to keep constant the temperature and the physical dimensions, and thereby keep constant 10 the inter-electrode capacity and oscillation frequency.

Another object is to provide means for reducing the power input to a vacuum tube during 15 spacing periods.

A further object is to provide means for stabilizing the voltage applied to the tube, and for adjusting the power input to different values during marking and spacing periods.

20 Still other objects of our invention are to provide means in connection with the plate power supply for changing the voltage during the operation of keying.

In the operation of vacuum tube transmitters, 25 especially at high frequencies, where the inter-electrode capacity is a substantial part of the capacity in the resonant circuit, difficulty has been experienced in maintaining this capacity constant during signalling, because of the fact that the energy dissipation in the tube varies 30 in magnitude between spacing and marking intervals. The change in energy dissipation in the tube results in a change in temperature of the electrodes, which change in temperature changes the physical dimensions and inter-electrode spacing, and thereby the inter-electrode capacity. 35 This results in a change in the overall capacity in the resonant circuit, which of course changes the oscillation frequency. The change in dissipation of energy in the tube may occur either with 40 or without a change in the plate current.

The frequency of oscillation not only changes with change in electrode temperature but also changes with the applied voltage. Accordingly, 45 if the tube is supplied from a motor generator set which changes its speed somewhat when the load is changed, an increase in plate current during spacing periods, by increasing the generator load, may reduce its speed and voltage, thus causing 50 the application of a decreasing voltage at the beginning of a marking period. While the change in generator speed between marking periods and spacing periods may be small, nevertheless at the higher frequencies of generation, even a few volts 55 change in generator voltage from a change of a

few revolutions per minute may produce a considerable number of cycles change in frequency, resulting in still further disturbance of the frequency stability. At high frequencies and when heterodyne reception is used these changes are 60 troublesome because of the change in beat note frequency in the heterodyne receiver, which makes the code less easy to read, as well as the reduction in signal strength from departure from exact resonance between signal and receiver. 65

Our invention provides simple means for adjusting the power input to the transmitter to different values during keying and spacing periods in such a way as to maintain the energy dissipation in the tube constant, whether the tube 70 is oscillating for a marking period or non-oscillating for a spacing period, thereby maintaining the electrode temperature and the oscillation frequency constant.

In addition our invention permits of working 75 the tube at a higher duty rate because of the fact that allowance does not need to be made for any greater energy dissipation in the tube than is incidental to the translation of power. Under the older systems the tube could be loaded 80 only to such a point that, when the added energy dissipation during spacing periods was allowed for, the temperature still would not exceed the permissible limit. This reduction in rated output might amount to a substantial portion 85 of the total power dissipating capacity of the tube. Our invention makes it unnecessary to allow any margin of this sort, and permits the tube to be loaded during oscillating periods to its maximum permissible limits without allowance 90 for increased dissipation during non-oscillating periods.

Other objects and structural details of our invention will be apparent from the following description when read in connection with the accompanying drawing, wherein

Fig. 1 shows a simple embodiment of our invention utilizing a relay and resistances.

Fig. 2 shows a similar embodiment with the addition of a generator for filament heating. 100

Referring to Figure 1, our invention includes a vacuum tube 1, with which is associated a tuning circuit 2, and a grid inductance 3, a grid choke 4, shunted by a chopper 5 in circuit with the contacts of a keying relay 6, for opening and closing the shunt.

Any convenient current supply may be utilized for heating the filament, such as a generator, or batteries, etc. Plate circuit power is provided from any convenient source which may be a high volt- 110

- age generator 7 driven by a suitable device such as a motor 21 connected to the mains 23. A radio frequency choke coil 8 is desirably included in the generator circuit as shown to prevent the flow of stray radio frequency currents into the power supply system. A plate circuit relay 9 is also provided and connected to the key circuit in parallel with the keying relay 6. The relays 6 and 9 are operated by energy from a suitable source such as a battery 10, under the control of a key 11.
- A resistance 12 is connected between the positive terminal of the generator 7 and the plate circuits of the tube 1. The positive lead of the generator 7 is also connected to the tongue of the relay 9, and the plate circuit of the tube 1 is connected to one of the relay contacts 15. A second resistance 14 is also provided, and connected between the negative terminal of the generator 7 and the other contact 16 of the relay 9.
- In the operation of this embodiment of our device, closure of the key 11 energizes the relay 6, closing the shunt around the choke 4. The grid coil 3 and plate tuning circuit 2 then cause the production of marking oscillations in the tube 1 which may be broken up into pulses at an audible frequency by the chopper 5 or which may be made continuous by omitting or shorting out chopper 5. Simultaneously the relay 9 is energized, drawing the tongue against the contact 15, thus disconnecting the resistance 14 from across generator 7, and short-circuiting the resistance 12, thereby applying full voltage to the tube 1 for the production of oscillations. When the key 11 is opened for a spacing period, releasing relay 6, the grid choke 4 is inserted in the grid circuit of the tube 1, choking out the oscillations which otherwise would flow to the grid, and preventing oscillation of the tube. Under these conditions, the plate current may change, and the plate dissipation increases by an amount determined by both the change in current, if any, and the amount of energy previously delivered to the aerial. The increase in energy dissipation in the tube, raises its temperature, causing expansion of the elements, and thereby alters the spatial separation of the electrodes. This would change the inter-electrode capacity, and thereby the total capacity in the resonant circuit. If the relay 6 is then re-closed for a second marking period, these changes would cause the renewed oscillations to be at a slightly different frequency than the oscillations at the close of the previous marking period.
- This tendency is, however, prevented by the relay 9, and its connected circuits. When the key 11 is opened, releasing the relay 6, oscillations are choked out by the choke 4. Simultaneously the relay 9 is released, opening the short-circuit around the resistance 12, thereby placing it in the plate circuit and reducing the plate voltage applied to the vacuum tube. The adjustment of resistance 12 is such that the energy dissipation in the tube is the same during spacing as during marking periods.
- The insertion of the resistance 12 in the plate circuit reduces the current in the generator 7 and the load on the motor 21. This may cause a substantial change in generator speed, depending on the regulation of the driving motor, and a change in the resultant voltage of generator 7. It is of course obvious that during rapid keying, the inertia of the motor and generator armatures is sufficiently great to limit the changes to comparatively small values, but also during pauses in transmission there may be sufficient time for the generator speed to attain an equilibrium value at

the reduced load. This changed speed and also the voltage regulation characteristic of the generator, then is effective for the generation of a different voltage at the beginning of the next marking period, which likewise tends to produce a change in frequency. This tendency toward change in oscillation frequency is most easily compensated for by maintaining the load upon the generator constant by the addition of a load through a resistance 14 as shown.

The resistance 14 is shunted across the generator terminals during spacing periods by contact of the tongue of relay 9 against the contact 16, whereby it serves to maintain the load on the generator 7 constant in order to prevent voltage variations during the spacing and keying intervals. The resistance 14 may likewise be adjusted to such a value that the current which flows through it is substantially equal to the difference in current flowing through the tube between spacing and marking periods.

By the construction of the device of our invention, we are thus enabled to maintain the energy dissipation in the tube 1 constant through both spacing and marking periods, and thereby stabilize its oscillation frequency, and likewise we are enabled to maintain the load upon the plate generator, and its voltage, constant through the entire transmission period, avoiding the fluctuations in speed and voltage which would otherwise occur due to the change in plate dissipation in the tube.

It may be noted that the tongue and contacts of the relay 9 are connected on the positive side of the generator 7 and are accordingly at a maximum potential from ground; and from the coil of the relay. This fact necessitates care in insulating the relay tongue and contacts, resulting in a requirement for an expensive constructed relay. It is obvious that the relay may be placed at ground potential by inserting resistance 12 between the negative terminal of generator 7 and grounded filament connection to tube 1.

Fig. 2 discloses an embodiment similar to Fig. 1, except that filament power is obtained from a three unit motor generator set, consisting of plate generator 7, motor 21 and filament generator 22, mains 23 supplying current to motor 21. The load on generator 7 being constant, the generator will cause no change in speed of the motor and consequently the voltage supplied by filament generator 22 will be constant, thus maintaining the filament at a constant temperature. The frequency generated, being greatly affected by the temperature of the filament, it will follow that, when using a three unit motor generator, the non-reaction of the plate generator on the motor, permitting a constant voltage output of the filament generator, will result in great frequency stability.

By the various embodiments of the device of our invention, we are thus enabled to obtain a uniform dissipation of energy in a vacuum tube and avoid change of dissipation between spacing and marking periods, thereby maintaining the temperature substantially constant, which constantly materially aids in maintaining the inter-electrode capacity and the oscillation frequency constant. Simultaneously, we are enabled to maintain the plate and filament generator voltages constant, thus facilitating stabilization of frequency.

Use of our invention for stabilizing the frequency of vacuum tube oscillator transmitters results in reduction of interference to communi-

cations on adjacent frequency channels and improves reception of signals from transmitters thus equipped.

While we have disclosed several embodiments 5 of the device of our invention, it is possible to produce still other embodiments of the same inventive concept without departing from the spirit thereof and we desire therefore that the appended claims be limited only to the extent 10 required by the prior art or stated therein.

We claim as our invention:

1. In a radio transmitter, the combination of an electron tube oscillation generator having coupled input and output circuits, a generator for supplying current to said output circuit, signalling means for providing marking and spacing signals, means for causing the energy dissipation in the tube to be the same during spacing as during marking periods, means controlled 15 by the signalling means for causing the tube to cease generation of oscillations during spacing periods and to produce oscillations during marking periods, and means for equalizing the load on said supply generator during marking and 20 spacing periods.
2. In a radio transmitter, the combination of an electron tube provided with a grid circuit and a plate circuit coupled in feed back relation for producing oscillations, a generator for supplying current to said plate circuit, means for producing marking and spacing signals, means for increasing the voltage of said current to said plate 25 circuit during marking periods, means associated with said grid circuit for choking out oscillations in said tube during spacing periods, and means for equalizing the load on said supply generator during marking and spacing periods.

tions in said tube during spacing periods, and means for equalizing the load on said generator during marking and spacing periods.

3. In a radio transmitter, the combination of an electron tube oscillation generator having coupled input and output circuits, a power source for said output circuit, signalling means for providing marking and spacing signals, a resistance element connected to said power source and connected in and out of the plate circuit under control of the signalling means and being of such value as to cause the energy dissipation in the tube to be the same during spacing as during marking periods, and means controlled by the signalling means for causing the tube to cease generation of oscillations during spacing periods and to produce oscillations during marking periods.

4. In a radio signalling arrangement, the combination of an electron oscillation generator having coupled input and output circuits, a power source for said output circuit, signalling means for providing marking and spacing signals, a choke coil under control of the signalling means connected in the input circuit during spacing 95 periods to cause the tube to cease generation of oscillations and removed from the input circuit during marking periods thereby allowing the tube to produce oscillations, and means for increasing the voltage supplied from said power 100 source to said output circuit during marking periods.
